INVENTOR:

George Ingram
By Richard C. Grier
Attest.

UNITED STATES PATENT OFFICE.

GEORGE INGRAM, OF LONDON, ENGLAND, ASSIGNOR TO STANLEY C. BIAS, NOW KNOWN AS PETER BIAZ, OF HARRISBURG, PENNSYLVANIA.

COMBINED TOY AND SWEETMEAT.

Application filed October 3, 1922. Serial No. 592,012.

To all whom it may concern:

Be it known that I, GEORGE INGRAM, a subject of the King of Great Britain, of 161 Parnell Road, Old Ford, London, England, residing at London, England, have invented certain new and useful Improvements in a Combined Toy and Sweetmeat, of which the following is a specification.

The subject of this invention is a combined toy and sweetmeat, adapted to enable 10 a child (or other person) whilst enjoying the pleasure of absorbing the sweetmeat by suction, to derive amusement from, in effect, blowing bubbles.

15 The combined toy and sweetmeat of the present invention consists of an inflatable balloon having a mouthpiece constituted by a tube formed of a soluble and masticable confectionery substance such as liquorice.

20 In the accompanying drawings, Figures 1 and 2 are side elevations of one example of the combined toy and sweetmeat, shewing the balloon in the deflated and inflated conditions respectively.

25 *a* is a balloon made from thin elastic indiarubber such as is used to form the well-known toy air-balloons, the balloon having an apertured neck *b* into which is inserted a mouthpiece constituted by a tube *c* formed 30 of liquorice. The tube *c*, which may be of any convenient length, and of suitable diameter, is preferably secured within the neck *b* by the contraction of the latter about the end of the tube, the neck being for this purpose made of a size to require being sprung over the tube.

The person using the combined toy and sweetmeat places the outer end of the tube *c*

in the mouth and, whilst sucking or masticating the liquorice whereof the tube is 40 formed, can derive amusement by inflating the balloon *a* by means of the breath, as in blowing soap-bubbles.

I claim:—

1. A tubular confection with an inflatable 45 toy balloon attached adjacent one end thereof and inflatable by blowing through the tubular confection.

2. A combined toy and sweetmeat consisting in the combination with an inflatable 50 balloon, of a mouthpiece therefor including a tube formed of a confection.

3. A combined toy and sweetmeat, consisting in the combination with an inflatable balloon, of a mouthpiece therefor constituted 55 by a tube formed of a soluble and masticable confectionery substance.

4. A combined toy and sweetmeat, consisting in the combination of an inflatable balloon formed of thin elastic material having an apertured neck, and a mouthpiece therefor constituted by a tube formed of a soluble and masticable confectionery substance secured within said neck by the contraction of the latter about one end of the 65 tube.

5. A combined toy and sweetmeat, consisting in the combination of an inflatable balloon formed of thin elastic indiarubber and having a neck, and a mouthpiece therefor 70 constituted by a tube formed of liquorice secured to the balloon by insertion within the neck.

In testimony whereof I have affixed my signature.

GEORGE INGRAM.
